US00D353799S

United States Patent [19]

Speiser et al.

[11] Patent Number: Des. 353,799

[45] Date of Patent: ** Dec. 27, 1994

[54] **NETWORK ADAPTER CARD FOR
INTERCHANGEABLE TRANSCEIVER
MODULES**

[75] Inventors: **Benjamin T. Speiser, San Francisco;
Lloyd N. Oliver, Milpitas, both of
Calif.**

[73] Assignee: **3 COM Corporation, Santa Clara,
Calif.**

[**] Term: **14 Years**

[21] Appl. No.: **8,446**

[22] Filed: **May 17, 1993**

[52] U.S. Cl. **D13/182**

[58] Field of Search 361/728, 736, 737, 741,
361/748, 752, 756, 760; 385/27, 31, 51; 439/55,

[57] **CLAIM**

The ornamental design for a network adapter card for interchangeable transceiver modules, as shown and described.

DESCRIPTION

FIG. 1 is a perspective view of a network adapter card for interchangeable transceiver modules showing our new design;

FIG. 2 is a top plan view thereof;

FIG. 3 is a front plan view thereof;

FIG. 4 is a left side plan view;

FIG. 5 is a right side plan view;

FIG. 6 is a bottom plan view thereof;

FIG. 7 is a rear plan view thereof; and,

FIG. 8 is a front plan view thereof showing our design with a network adapter card. The broken line showing of the adapter card is included for the purpose of illustrating environmental structure only and forms no part of the claimed design.

FIG. 2.

FIG. 4.

FIG. 3.

FIG. 5.

FIG. 6.

FIG. 7.

FIG. 8.
